UNITED STATES PATENT OFFICE.

HENRY HUGH MORGAN, OF WOODLAWN, ALABAMA.

ATTACHMENT FOR PLANERS.

No. 918,889.

Specification of Letters Patent.

Patented April 20, 1909.

Application filed February 24, 1908. Serial No. 417,473.

To all whom it may concern:

Be it known that I, HENRY HUGH MORGAN, residing at Woodlawn, in the county of Jefferson and State of Alabama, have invented certain new and useful Improvements in Attachments for Planers, of which the following is a specification.

My invention relates to certain new and useful improvements in attachments for planing machines and the like and it primarily seeks to provide an attachment which will enable the ordinary planing machine to plane circular arcs and more especially enable such machine to plane and cut out links for locomotives and the like.

My improved planer includes a bed plate adapted to be attached to the bed plate of the planer, a face plate carried by the bed plate to which the article operated upon is adapted to be secured, a supporting arm attached to the planer which carries a guide that has a slideway to coöperate with a corresponding member on an arm attached to the face plate so that as the bed plate of the planer is reciprocated the face plate of the attachment will be turned on its center so that the stationary cutting tool can operate upon the work to cut a surface of a circular arc form.

My invention also embodies certain detailed features of construction, all of which will be first described in detail and then be specifically pointed out in the appended claims reference being had to the accompanying drawings, in which:

Figure 1, is a perspective view of a planer embodying my invention. Fig. 2, is a top plan view thereof. Fig. 3, is a central, vertical, longitudinal section on the line 3—3 of Fig. 2. Fig. 4, is a detail perspective view of the bed plate of the attachment. Fig. 5, is a similar view of the face plate and its arm. Fig. 6, is a detail perspective view of the guide arm or support. Fig. 7, is an enlarged detail view showing the manner of graduating the slotted guide.

Referring now to the accompanying drawings in which like letters and numerals of reference indicate like parts in all the figures, 1 designates the planer which may be of the ordinary construction and embodies the stationary bed plate 1^a and the vertical supports 1^b that are connected by the tool carrying slideway 1^c in the ordinary manner. The

stationary bed plate 1^a has grooves 1^d to co-operate with the tracks 1^e on the sliding bed plate 1^f which is adapted to reciprocate along the stationary bed plate 1^a. The tool carriage 2, which may be of any approved construction, is mounted on the slideway 1^c and is adjustable thereon in the usual manner, the tool 2^a being feedable by a screw 2^b.

3 designates a part of my attachment which is the guide arm that may be secured to any stationary part of the planer, but is preferably secured to the tool receiving bar 1^c by the clamp 3^a and set screw 3^b, as indicated, the arm 3 terminating in an apertured eye portion 3^c, through which a bolt 4 passes, a washer 4^a being interposed between the bolt head and the eye 3^c for the usual purposes.

5 designates the guide bar which has a slideway 5^a, on its under face and a graduated dial portion 5^b to coöperate with the eye portion 3^c of the arm 3, a suitable indicating mark 3^d being provided thereon for that purpose. The eye portion 3^c is also provided with a pair of slots 3^e to receive the set screws 5^f on the guide 5 to lock the guide in its various adjusted positions.

6 designates the bed plate of my attachment, which bed plate is securable to the movable bed plate 1^f of the planer and in its preferred form the attachment bed plate 6 is of circular shape and provided with an annular groove 6^a into which the clamping plates 6^b project, the clamping plates 6^b being secured to the bed plate 1^f of the planer by bolts and nuts 5^c, as indicated.

6^d designates a circular dove-tailed portion formed in the upper surface of the attachment bed plate 6 to receive the correspondingly formed fulcrum member 7^a of the face plate 7 which forms a part of my attachment, and in order to get the pivot portion 7^a of such face plate into the dove-tailed circular portion 6^d of the bed plate 6 of my attachment, I provide a removable portion 6^e on said bed plate which is normally held in position by a set screw 6^f, as indicated. The face plate 7 on its work receiving face is provided with the usual guide grooves 7^b, by means of which and clamps 8, together with bolts and nuts 9, the work 10 may be securely bolted to the face plate.

Secured to the face plate 7 is an arm 11 that is rigidly held to the face plate and at

its free end is formed with an eye portion 11^a, through which the bolt 12 passes, the bolt 12 at one end carrying a swiveled bridge member 12^a to which a pair of spaced friction 5 rollers 12^b are secured and the bolt 12 is held in place on the face plate arm 11 by the nuts 12^c, as indicated. The friction rollers 12^b project into the slotted portion 5^a of the guide bar 5 and coöperate therewith.

10 In the practical arrangement of my invention, the pivot center of the guide 5 and that of the face plate 7 lie in the central vertical plane of the movable bed plate 1^f of the planer so that when the guide 5 lies in alignment with such central plane and the movable bed plate 1^f is reciprocated in the usual manner, no rotary movement is imparted to the face plate 7 of my attachment, but when the guide 5 is set at an angle to such central 15 plane of the planer, then a corresponding rotary or oscillating motion is imparted to the face plate 7 as the movable bed plate 1^f of the planer is reciprocated and the degree of such oscillation will vary in proportion to 20 the angle to which the guide 5 is adjusted.

In the practical application of my invention, the bed plate 6 of my attachment is bolted down securely to the movable bed plate 1^f of the planer, and the arm 3 secured 30 in place, after which the guide 5 and the arm 11 are coöperatively connected and the guide set to the proper angle. The work 10 to be operated upon is then clamped to the face plate 7 of the attachment and the power applied to reciprocate the bed plate 1^f, it 35 being understood that the tool 2 is adjusted as may be desired to operate upon the work 10. As the bed plate 1^f is reciprocated the proper motion is imparted to the face plate 40 of my attachment with the result that as the work comes into operative relation with the tool, the cut desired will be made, as will be readily understood from the drawings.

From the foregoing description, taken in 45 connection with the accompanying drawings, it is thought the complete construction, operation and numerous advantages of my invention will be readily understood by those

skilled in the art to which the invention ap- 50 pertains.

What I claim is:

1. An attachment for planers comprising a bed plate securable to the reciprocating bed of the planer, an adjustable guide having a slideway, a face plate pivotally connected with the bed plate and coöperatively connected with the guide, said coöperative connection with the guide including an arm secured to the face plate, a bridge member pivotally connected with the arm and coöperatively connected with said guide.

2. An attachment for planers comprising a bed plate securable to the reciprocating bed of the planer, an adjustable guide having a slideway, a face plate pivotally connected with the bed plate and coöperatively connected with the guide, said coöperative connection with the guide including an arm secured to the face plate, a bridge member pivotally connected with the arm and coöperatively connected with said guide, a fixed frame for supporting said guide, and means for pivotally connecting said guide to said fixed frame.

3. An attachment for planers comprising a bed plate securable to the reciprocating bed of the planer, an adjustable guide having a slideway, a face plate pivotally connected with the bed plate and coöperatively connected with the guide, said coöperative connection with the guide including an arm secured to the face plate, a bridge member pivotally connected with the arm and coöperatively connected with said guide, a fixed frame for supporting said guide, means for pivotally and adjustably connecting said guide to said fixed frame, said connection including a portion having a graduation to coöperate with graduations on said guide to indicate the position of the guide with relation to said connecting means.

HENRY HUGH MORGAN.
